UNITED STATES PATENT OFFICE.

EDMUND H. LUNKEN, OF CINCINNATI, OHIO.

WINDOW CONSTRUCTION.

SPECIFICATION forming part of Letters Patent No. 769,803, dated September 13, 1904.

Application filed January 26, 1904. Serial No. 190,730. (No model.)

To all whom it may concern:

Be it known that I, EDMUND H. LUNKEN, a citizen of the United States, residing at Cincinnati, Ohio, have invented certain new and 5 useful Improvements in Window Constructions, of which the following is a specification.

My invention relates to window constructions, and I have shown it embodied in the general style of window disclosed in applications for Letters Patent of the United States, filed by Bernard J. Hausfeld and myself as joint inventors, September 14, 1903, Serial No. 173,118, and January 9, 1904, Serial No. 188,199.

15 In the window constructions referred to a metallic main frame is arranged in the window-opening and carries pivotally a secondary frame arranged to swing into different positions. My present invention concerns more particularly a blind or shutter arrangement 20 in connection with the window whereby the entrance of the light-rays may be regulated and different lighting effects secured and whereby also when the secondary frame is 25 swung on its pivots into an inclined position the blinds or shutters may serve as an awning and one that is capable of adjustment as desired.

The invention consists in the features and 30 combination and arrangement of parts hereinafter described, and particularly pointed out in the claims.

In the accompanying drawings, Figure 1 is a central vertical sectional view of a window construction with my invention combined therewith. Fig. 2 is a perspective view in detail, partly in section. Fig. 3 is a sectional plan view through one of the shutter-carriers with one of the blinds or shutters removed. 40 Fig. 4 is a view of a detail.

In the drawings, 1 is the main frame, and 2 the secondary frame, pivoted to the main frame at 3, so that it may be swung in a vertical plane into different inclined positions.

45 My blind or shutter arrangement comprises two carriers 4 and 5, adapted to run in guide-ways 6 7, extending vertically of the secondary frame directly adjacent each other and parallel. The carriers are connected with 50 each other by a cord 8 or other flexible me-

dium extending over a guide-pulley 9 and having its ends connected to the carriers, so that they may be moved in unison. Each carrier has a plurality of shutters or sun-blinds thereon, and I have shown three of these. 55 The one marked 10 is fixed to the carrier at a point about midway of its height, while the other two are movable in guide-grooves 11, extending vertically near opposite edges of the carrier and parallel with each other. The 60 movable blinds or shutters of each carrier are connected by a cord 12, passing over a pulley 13 at or near the top of the carrier, so that they will move in unison, and when one is raised the other will fall. In addition to these 65 blinds or shutters I also employ a sun-shade or blind 14, connected with a spring-roller 15, journaled in bearings on the upper carrier, said sun-shade depending from the upper carrier and being capable of being drawn down 70 to the point desired like an extensible curtain.

As shown in Fig. 1, when the shutter-carrier 4 is all the way down the other carrier, with its shutters or blinds, is all the way up; but by raising the lower carrier the upper 75 carrier will be allowed to descend, and thus the shutters may be adjusted to various positions vertically to secure different shading effects. Further than this each set of shutters—*i. e.*, those supported on each carrier— 80 is capable of adjustment to afford different ventilating or shading effects. For instance, the set of shutters on the upper carrier are shown as spread out in relation to each other to obstruct the opening at the top of the window, while the set of shutters or blinds on the lower carrier are assembled in relation to each other, the two movable members being arranged at the sides of the fixed member, thus presenting a minimum obstruction to the 85 opening at this point. The two sets of shutters may be brought to a central position side by side, and each set may in itself be assembled so that the obstructions at the center of the window-opening will then be equal 90 only to the height of a single shutter section or member, or either or both sets may be spread to a greater or less degree, and the carriers themselves may be separated vertically to any desired extent. In this way va- 100

rious degrees and conditions of ventilation may be secured, and the same is true of the shading effects.

I prefer to form the adjustable shutter-sections of metal and in the form of plates having their side edges running in the grooves of the carrier in the case of the movable shutters, and in case of the fixed shutters the side edges are simply embedded in the carriers.

10 These plates are provided with inclined slats of substantially ordinary form.

Leaf-springs 16 are secured to one edge of the bottom shutter in each carrier, and spring 17 is likewise secured to one edge of the bottom carrier. The frictional restraint afforded by these springs prevents the shutters from jarring open and also in case of a slight over-weight will hold the shutters in position. Also when it is desired to wash the windows 20 on their exterior side the frame is swung vertically when horizontally pivoted, and unless some provision was made to hold the bottom shutters and lower carrier in place they would by gravity fall to the bottom. I also provide 25 a stop 19 on each carrier at the top of the grooves for each movable shutter, so as to prevent their falling out when the secondary frame is reversed. To insure the bottom carrier from falling when the window is swung, 30 I provide a lock 18 on the carrier.

It will be seen that with my invention when the secondary frame is in closed position ventilation may be had at the top of the window without causing the draft to affect the flexible curtain to any annoying extent by simply lowering the upper sash, say, to the plane of the lower end of the upper carrier. The air-current will now pass entirely above the curtain through the slatted shutters or more 40 freely through the spaces, which may be provided at will by adjusting the said shutters to their middle position. Further, the flexible curtain follows the adjustment of the upper member of the blind or awning, being attached 45 to the carrier thereof, and it will be further noticed that the flexible curtain is used to shield the space between the upper and lower main members of the blind, and thus the whole window may be controlled as to the 50 passage of the light. When it is desired to wash the inside of window, both carriers can be pushed up above the bottom window, as they are made light in weight, and can be easily locked in that position until the window is cleaned, for which purpose the upper carrier may be provided with a lock, as well as the lower.

In applying my invention to that form of window in which the sash balance each other 60 the carriers 4 and 5 would be of a size sufficient to cover the openings at top and bottom of window when the sash are directly opposite each other. By this means a perfect circulation of air is obtained, and the sun is entirely excluded when the curtain 14 is low-

ered. As the sash at all times shield the curtain from the direct current of air, the annoyance of a swinging curtain is overcome.

With my improved arrangement of shades quite a number of combinations of shade effect can be obtained, and it can be applied to great advantage to the present form of wooden windows operated by weights. In other words, I do not limit myself to any particular style of window with which my invention is associated.

Instead of a plurality of shutters, as heretofore described, it is evident that the carriers 4 and 5 need have but one shutter attached thereto for a more simple form of blind 70 when desired, this being considered no departure from my invention.

It is evident that the lower blind can be dispensed with and the upper blind remain at the top of the window in which a plurality of 80 shutters can be arranged and operated by a cord. The curtain then would have to be longer, so as to cover the opening between the shutter and sill.

I do not wish to limit myself to the arrangement in which the balanced shutters move on opposite sides of the stationary member, as a different arrangement may be employed.

It will be understood that the light-shade or blind described above also answers the purpose of an awning when the swinging frame is adjusted to inclined position, and the terms "light-shade" and "blind" are meant to cover such use of these parts.

I claim—

1. In combination with a window, a carrier movable vertically and a plurality of shutters or blinds moving in guideways on the said carrier, substantially as described.

2. In combination with a window, a carrier movable vertically and having guideways and an adjustable shutter or blind carried thereby and movable in said guideways, substantially as described.

3. In combination with a window, a carrier movable vertically and having guideways and a plurality of shutters carried thereby, one of which is slidable in said guideways and is adjustable in relation to another, substantially as described.

4. In combination with a window, a carrier movably supported thereon and fixed and movable shutters or blinds on the said carrier, substantially as described.

5. In combination with a window, a carrier movably supported thereon, a fixed shutter on the carrier, and a pair of movable shutters, said movable shutters being movable on opposite sides of the fixed shutter or blind, substantially as described.

6. In combination with a window, a movable carrier and a plurality of shutters or blinds on the carrier including a fixed blind and a pair of movable blinds, the said movable blinds having a flexible connection between them where-

by the said blinds move in unison, substantially as described.

7. In combination in a window construction, with a main frame, a secondary frame pivotally mounted in the main frame and an adjustable light-shade carried by the secondary frame and composed of a plurality of adjustable members, substantially as described.

8. In combination in a window construction, 10 a main frame, a secondary frame pivotally mounted therein and a light-shade guided in the secondary frame, said light-shade comprising a plurality of members, one of which is adjustable in relation to another, substantially 15 as described.

9. In combination in a window construction, a main frame, a secondary frame pivoted therein and a light-shade carried by the secondary frame and having one portion near the top of 20 the secondary frame and another portion near the bottom, said portions being adjustable, substantially as described.

10. In combination in a window construction, a main frame, a secondary frame pivoted 25 therein, parallel guides on the said secondary frame and a light-shade having one member moving in one of the guides and another member moving in the other guide and a connection between the said members, substantially 30 as described.

11. In combination with a window, an extensible curtain and an adjustable light-shade above the said extensible curtain, said curtain moving with the said light-shade, substantially 35 as described.

12. In combination in a window, a carrier, an extensible curtain or shade carried thereby and an adjustable light-shade on the carrier, substantially as described.

40 13. In combination in a window, a verti-

cally-movable carrier, an extensible curtain supported at the lower part of the said carrier and means on the carrier for regulating the ventilating-opening above the said curtain, substantially as described.

45

14. In combination with a window, a light-shade comprising an adjustable member near the top of the window and an adjustable member at or near the bottom of the window, and an extensible curtain to control the space between the said members, said curtain being carried by the adjustable upper member, substantially as described.

50

15. In combination in a window, the upper and lower carriers each having thereon an adjustable member or members, and an extensible curtain supported on the upper carrier depending therefrom and arranged to control the space between the carriers, substantially as described.

55

16. In combination, in a window construction with a sliding sash, a slatted light-shade and an extensible curtain at the lower part thereof, the said slatted light-shade being arranged to shield the space over the top of the upper sash when lowered while the extensible curtain extends over the front of the sashes, substantially as described.

60

17. In combination, with a window, a shutter-section, supporting means therefor fitted in the window-frame and to which the said shutter-section is fixed, said supporting means having guideways and shutters movable in the guideways of said supporting means.

70

In testimony whereof I affix my signature in presence of two witnesses.
